HOLDER FOR SILVERWARE AND THE LIKE

Edward A. Stiller, 66 Beverly Road, Brookline, Mass.

Filed Dec. 22, 1960, Ser. No. 63,415

Term of patent 14 years

(Cl. D58—26)

F I G. 1

F I G. 2

F I G. 3

FIG. 1 is a side view in perspective of a holder for silverware and the like embodying my new design;

FIG. 2 is a top plan view thereof; and

FIG. 3 is a bottom plan view thereof.

The side not shown is the same as the side shown.

I claim:

The ornamental design for a holder for silverware and the like, as shown and described.
